(57) **CLAIM**

The ornamental design for a chair, as shown and described.

DESCRIPTION

FIG. 1 is a perspective view of a chair embodying my design, showing the front and left sides thereof;
FIG. 2 is a front elevational view of the chair;
FIG. 3 is a rear elevational view of the chair;
FIG. 4 is a right side elevational view of the chair; and,
FIG. 5 is a left side elevational view of the chair.
The broken lines immediately adjacent the shaded areas represent the bounds of the claimed design, while all other broken lines are for illustrative purposes, the broken lines forming no part of the claimed design.

1 Claim, 5 Drawing Sheets
